UNITED STATES PATENT OFFICE.

ALBRECHT ADELMANN, OF NEW YORK, N. Y.

BOW-FACING OARLOCK.

Application filed February 20, 1924. Serial No. 693,962.

To all whom it may concern:

Be it known that I, ALBRECHT ADELMANN, a citizen of Germany, residing at New York city, borough of the Bronx, in the county of Bronx and State of New York, have invented certain new and useful Improvements in Bow-Facing Oarlocks, of which the following is a specification.

This invention relates to the propulsion of boats and has particular reference to means for supporting hand operated oars so as to enable the boatman to face toward the bow of the boat while rowing forward.

Among the objects of the invention, therefore, is to provide a special construction of oars and oarlocks so as to enable the boatman to sit in the boat facing toward the bow and have the same control for the manipulation of the oars as is customary with the usual oars which demand that the boatman sit with his back toward the bow, thus enabling the boatman with the new equipment to have always a clear and direct vision of the course ahead of him so as to better avoid collisions or obstructions.

Another object of the invention is to provide a novel form of jointed oar having the same universal movement in connection with the lock as the common oar has and having specially arranged supporting means enabling the oars to be shipped or swung around into the boat with facility.

With the foregoing and other objects in view the invention consists in the arrangement and combination of parts hereinafter described and claimed, and while the invention is not restricted to the exact details of construction disclosed or suggested herein still for the purpose of illustrating a practical embodiment thereof reference is had to the accompanying drawings, in which like reference characters designate the same parts in the several views, and in which—

Figure 1 is a plan view of a fragment of a boat having my improvement attached thereto, a portion of the structure being in section on the broken line 1—1 of Fig. 2.

Fig. 2 is a side elevation of the same, parts being in section about on the broken line 2—2 of Fig. 1.

Fig. 3 is an end elevation of Fig. 2.

Fig. 4 is a diagram indicating the arrangement and operation of the oars of a boat.

Referring now more specifically to the

drawings I show a conventional row boat 10 having right and left side rails 11 and a seat 12 for the boatman, and to the rails 11 are secured the oarlocks constituting the subject matter of this specification.

13 indicates a bracket fitted upon the rail 11 in any suitable manner as by means of ears or lugs 14 extending down upon the inside of the rail through which fasteners 15 are passed securing the same in fixed position. Other fasteners such as screws 16 may be driven down into the top of the rail. One end of the bracket is in the form of a yoke 17 having an open mouth directed toward the opposite end of the bracket and in this mouth is journaled a knuckle 18 for movement around a vertical axis, and the knuckle has an open horizontal bearing socket 19 adjacent to the open end of the yoke. The yoke, furthermore, has vertically aligned bearing holes 20 and 21 formed therein. At the opposite end the bracket is provided with an enlargement or head 22 having a horizontal 80 and longitudinally arranged passage-way 23 and an undercut or open side at 24. A plunger 25 is located in the longitudinal passage 23 and is normally urged toward the opposite end of the bracket by means of a spring 26. It may be drawn, however, manually in the opposite direction by the operator while pulling upon the head 25 of the plunger.

Another main feature of construction is a bail 27, one end 28 of which extends vertically downward through the hole 20 of the yoke and the vertical hole 29 in the knuckle and thence into the hole or socket 21 of the yoke, constituting the vertical bearing or axis for the knuckle. A pin 30 of any suitable construction typifies suitable means for securing the bearing end 28 in the place indicated. The bail extends thence horizontally toward the opposite end of the bracket and is bent thence downward forming a bearing 31, the extreme end 32 of which is bent horizontally and is projectable laterally through the opening 24 of the bracket head and is locked in such position by the end of the plunger 25 projected into a pit 33 formed in the end 32. Thus the bail becomes in effect a rigid part of the bracket when so locked by the plunger. Upon withdrawing the plunger, however, the bail may swing around the axis of the end 28 thereof. The bearing 31 includes

a movable section 31^a shown as connected to the main portion by means of a hinge 31^b, but normally locked in closed position by means of a fastener such as a screw 31^c.

5 Another main portion of the improved oarlock consists of a tilting member or casing comprising upper and lower plates 34 and 35 arranged in parallel planes and held in fixed relation to each other by means of 10 stop or trunnion blocks 36 and 37 of a rigid construction and specially designed to constitute means to limit the swing of the oar members and also provided each with a bearing trunnion 38. These blocks may be constructed as castings or drop forgings and are 15 provided as indicated with top and bottom plane surfaces against which the inner surfaces of the top and bottom plates are fitted and through which rivets 39 are passed to 20 lock these parts together. One trunnion 38 is journaled in the bearing socket 19 of the knuckle at one end of the bracket and the other trunnion, being in axial alignment with the first mentioned trunnion, is journaled in the bearing 31. Thus the casing is 25 supported free to tilt as far as desired or necessary around a fore and aft axis within or beneath the bail 27.

The oar mechanism comprises a handle 30 portion 40 and a blade portion 41 for each oarlock, and the specific description of the connections between the two members of each oar will be understood as applicable to both sets. The handle 40 includes or is 35 fitted suitably to a metal shank portion 42 of relatively thin construction and curved as shown in Fig. 1. The outer end of this portion is fitted upon a vertical axis or pivot pin 43 fixed within or between the plates 40 44 and 35 of the casing. Formed preferably as an integral part of the shank 42 is a gear segment 44 the teeth of which are formed along an arc concentric with the axis of the pin 43 and normally directed 45 toward the opposite end of the casing. The pin 43 is located as close as practicable to the trunnion block 37 and the curved portion of the shank 42 co-operates with this trunnion block as a limiting stop for movement of the handle in the direction in which the stroke is made. The segment 44 lies 50 then over the shank 42 and the axis thereof lies substantially in the vertical plane of the axis of the handle.

55 The blade 41 is likewise formed with or attached to a metal shank 45 pivoted upon a pin 46 fixed vertically adjacent to the opposite trunnion block at 36, and this shank 45 is fixed rigidly to or formed integral with a gear segment 47, the teeth of 60 which mesh constantly with the teeth of the segment 44. While the limit of movement of the oar handle 40 in making a stroke is determined by the block 37, movement in 65 the opposite direction is limited preferably by impact of the curved portion of the shank 45 against the stop or trunnion block 36. There is no relative movement or lost motion vertically between the oar members and the casing, and because of the interengagement of the teeth of the segments and the close bearing fit of the same upon the pins 43 and 46 there is no lost motion between these relatively pivoted members. It follows, therefore, that a pull on the handle will cause a corresponding movement of the blade of the oar in the same direction and in the same plane. Also a downward movement upon the handle will lift the blade in exactly the same manner as the action 70 upon an ordinary stiff oar. In other words, a man seated upon the seat 12 facing forward will manipulate his oars with this improvement with exactly the same movements or motions as he would practice with common oars if seated facing the opposite way.

I have found it desirable to provide means whereby a relatively short stroke of the handle may produce a longer stroke of the oar blade or a relatively slow movement of the handle will produce a quicker movement of the blade. To this end I have constructed the segments 44 larger in radius than the segments 47. Consequently it must be appreciated that for the making of a sufficiently longer or full stroke of the blade, the handle 40 need move through a shorter arc before it is limited or stopped.

It will be noted from the foregoing that the casing is provided with open sides 100 through which the handle and blade members of the oar project laterally and along which they swing simultaneously in the same direction and also that the pivots for these parts are located on opposite sides of 105 the fore and aft axis around which the casing is adapted to tilt. Furthermore, the respective pivots for the oar parts are so located that the axis around which the casing tilts is located between them and said parts, 110 whereby there is afforded the equivalent of relatively long oar members.

I claim:

1. In a bow facing oarlock, the combination of a bracket, a casing above the bracket and including bearing blocks having axial trunnions, means borne by said bracket supporting the casing trunnions for tilting movement of the casing around a substantially fore and aft horizontal axis, oar means pivotally mounted within the casing, the bearing blocks serving as stops for limiting the swinging of the oar means.
2. Mechanism as set forth in claim 1 in which the bracket is provided at one end with a yoke having an opening toward the opposite end, a knuckle in said yoke, a bail having one end passing through said knuckle and said yoke and constituting a pivot for the swinging of the knuckle.

around the axis of such end, and means detachably locking the opposite end of the bail to the opposite end of the bracket.

3. The herein described oarlock structure comprising, in combination, a casing having open sides, a pair of pivots mounted in the casing perpendicular to the top and bottom thereof, a pair of blocks at the ends of the casing adjacent to the respective pivots, said blocks having oppositely projected trunnions determining the fore and aft axis of the casing, an oar handle on one side of said pivots and projecting laterally through one open side of the casing, an oar blade pivoted on the other pivot and projected from the opposite side of the casing, means connecting said handle and blade for simultaneous pivotal movement thereof in the same direction independently of the tilting thereof with the casing around the axis aforesaid, and means to support said trunnions for the tilting movement of the casing, said means for connecting the handle and blade being two toothed segments lying in a plane above the plane of the oar members and mounted to swing around pivots lying in the vertical planes of the axes of the respective members.

4. In a bow facing oarlock, the combination of a bracket, a casing above the bracket, means supporting the casing for tilting movement around an axis parallel to the bracket, said casing comprising upper and lower plates and a pair of end blocks, the end blocks having bearing members coinciding with the axis around which the casing tilts, an oar handle and an oar blade mounted to swing around pivots within the casing and perpendicular to the casing plates, the end members of the casing serving as limit-

ing stops for the swinging of the oar members, and relatively movable members connected to the respective oar members for causing simultaneous swinging thereof around their pivots.

5. Mechanism as set forth in claim 4 in which the bracket is provided at one end with a yoke having an opening toward the opposite end, a knuckle in said yoke, a bail having one end passing through said knuckle and said yoke and constituting a pivot for the swinging of the knuckle around the axis of such end, and means detachably locking the opposite end of the bail to the opposite end of the bracket.

6. The herein described oarlock structure comprising, in combination, a tilting member, a pair of pivots mounted thereon, means including oppositely projected trunnions determining the fore and aft axis around which the member is adapted to tilt, an oar handle pivoted on one of said pivots and projected laterally therefrom, an oar blade pivoted on the other pivot and projecting laterally from the opposite side of the tilting member, said fore and aft axis lying between the aforesaid pivots and the pivots for the oar parts being located on the remote side of the fore and aft axis from their respective oar parts, thus affording the maximum leverage for the easier manipulation of the oar, means connecting said handle and blade for simultaneous pivotal movement thereof in the same direction independently of the tilting of said tilting member around the axis aforesaid, and means to support said trunnions for the tilting movement of said member.

In testimony whereof I affix my signature.

ALBRECHT ADELMANN.
